UNITED STATES PATENT OFFICE.

FREDERICK THOMAS WILKES, OF BRANTFORD, CANADA.

SAWMILL LOG-TURNER.

SPECIFICATION forming part of Letters Patent No. 738,385, dated September 8, 1903.

Application filed February 9, 1903. Serial No. 142,560. (No model.)

To all whom it may concern:

Be it known that I, FREDERICK THOMAS WILKES, of the city of Brantford, county of Brant, Province of Ontario, Canada, have invented certain new and useful Improvements in Sawmill Log-Turners, of which the following is a specification.

The object of my invention is to devise simple and effective means for taking logs from the log-deck of the mill and placing them on the carriage and for turning them while on the carriage; and it consists, essentially, of a tooth-bar or nigger having operative connection with two steam-cylinders, one vertical and one horizontal, in such a manner that it may be moved vertically or swung on its lower end as a pivot or given a combination of the two movements, substantially as herein-after more specifically described and then definitely claimed.

Figure 1 is an elevation of a portion of a sawmill embodying my invention. Fig. 2 is a plan view of parts of Fig. 1. Fig. 3 is a plan view of the cross-head embracing the tooth or nigger bar. Fig. 4 is a side elevation of the same.

In the drawings like letters of reference indicate corresponding parts in the different figures.

Referring particularly to Fig. 1, A is the foundation-frame of the machine, on which the carriage B of the mill is adapted to run on suitable tracks.

C is the log-deck.

D is a vertical steam-cylinder provided, of course, with the usual piston and piston-rod E. A valve F is indicated in dotted lines, by means of which steam may be admitted to or exhausted from opposite ends of the piston in the ordinary well-known manner. At the upper end of the piston-rod is pivoted the lower end of the tooth-bar or nigger-bar G. This bar carries the pivoted teeth or dogs a, which are of ordinary construction and need not be particularly described.

H is a cross-head running on the guides b and adapted to guide the piston-rod E.

I is a horizontal cylinder located somewhat below the level of the carriage B. This cylinder is provided with the usual piston and the piston-rod J. It is also provided with a suitable valve K, by means of which steam

may be admitted to or exhausted from the opposite ends of the cylinder, as desired. To the end of the piston-rod J is secured the cross-head L, moving on suitable guides c. This cross-head, as shown particularly in Fig. 3, is notched or forked to receive the nigger-bar G. The open front of the notch or fork is closed by the cross-bar M, which is set in notches formed in the end of the cross-head. Secured to the ends of this cross-bar are the bolts N, passing through lugs d, formed on the cross-head. Suitable washers and nuts e are screwed on the ends of the bolts, and between the washers and nuts and the lugs d are placed coil-springs O. These springs thus tend to yieldingly maintain the cross-bar in its normal position, and their tension may be readily adjusted by means of the nuts e. Behind the nigger-bar in the cross-head is journaled a roller P.

The operation of the device is substantially as follows: Presuming the parts to be in the position shown in Fig. 1, if steam be admitted to the steam-cylinder D to raise the nigger-bar the latter slides through the cross-head L and turns a log resting on the saw-carriage. As the apparatus is intended not only to turn the log, but also to bring it from the log-deck onto the carriage, the nigger-bar must be brought into the position shown by the dotted lines in Fig. 1. This is done by admitting the steam into the cylinder I in front of the piston, thus carrying the cross-head back or away from the carriage. To push the log from the log-deck C onto the carriage, the nigger-bar is raised by admitting steam to the lower end of the cylinder D and at the same time is pushed toward the saw-carriage by admitting steam behind the piston of the horizontal cylinder I. The nigger-bar is thus used as a hammer to drive the log onto the carriage, and in consequence of this hammer action it is necessary to have the space between the cross-bar M and the roller P very little larger than the width of the nigger-bar to avoid hammering between the nigger-bar and the cross-head. When, however, the tooth-bar is in the position shown in dotted lines and is raised by the steam-cylinder D, the nigger-bar requires a larger space between the roller and the cross-bar, and it is for the purpose of allowing the cross-bar to

yield to give this necessary space that it is provided with the spring connections already described.

What I claim as my invention is—

- 5 1. In a device of the class described a nigger-bar, in combination with a steam-cylinder, to the piston-rod of which the lower end of the nigger-bar is pivotally connected; a substantially horizontal steam-cylinder; and a cross-head secured to the piston-rod of the said cylinder forked to embrace the nigger-bar; and spring means tending to maintain the nigger-bar in contact with the back of the fork, substantially as described.
- 10 2. In a device of the class described a nigger-bar, in combination with a steam-cylinder, to the piston-rod of which the lower end of the nigger-bar is pivotally connected; a substantially horizontal steam-cylinder, a cross-head notched or forked to receive the nigger-bar and secured to the piston-rod of the said horizontal cylinder; a cross-bar forming the closure for the said notch or fork; and springs adapted to yieldingly retain the cross-bar in its normal position, substantially as described.
- 15 3. In a device of the class described a nigger-bar, in combination with a steam-cylinder, to the piston-rod of which the lower end of the nigger-bar is pivotally connected; a substantially horizontal steam-cylinder; a cross-head notched or forked to receive the nigger-bar and secured to the piston-rod of the said horizontal cylinder; a cross-bar forming the closure for the said notch or fork; and springs adapted to yieldingly retain the cross-bar in its normal position, substantially as described.
- 20 4. In a device of the class described a nigger-bar, in combination with a steam-cylinder, to the piston-rod of which the lower end of the nigger-bar is pivotally connected; a substantially horizontal steam-cylinder, a cross-head notched or forked to receive the nigger-bar and secured to the piston-rod of the said horizontal cylinder; a cross-bar forming the closure for the said notch or fork; and springs adapted to yieldingly retain the cross-bar in its normal position, substantially as described.
- 25 5. In a device of the class described a nigger-bar, in combination with a steam-cylinder, to the piston-rod of which the lower end of the nigger-bar is pivotally connected; a substantially horizontal steam-cylinder, a cross-head notched or forked to receive the nigger-bar and secured to the piston-rod of the said horizontal cylinder; a cross-bar forming the closure for the said notch or fork; and springs adapted to yieldingly retain the cross-bar in its normal position, substantially as described.

ing the closure for the said notch or fork; 35 and adjustable springs adapted to yieldingly retain the cross-bar in its normal position, substantially as described.

4. In a device of the class described a nigger-bar, in combination with a steam-cylinder having a piston-rod to which the lower end of the nigger-bar is pivotally connected; a cross-head for the piston-rod and guides therefor; a substantially horizontal steam-cylinder having a piston-rod; a cross-head 45 notched or forked to receive the nigger-bar and secured to the piston-rod of the said horizontal cylinder; a cross-bar forming the closure for the said notch or fork; springs adapted to yieldingly retain the cross-bar in its 50 normal position; and guides for the last-mentioned cross-head, substantially as described.

5. In a device of the class described a nigger-bar; in combination with a vertically-movable part to which the nigger-bar is pivoted at its lower end; means for moving the said part; a cross-head notched or forked to receive the nigger-bar; a cross-bar forming the closure for the said notch or fork; springs adapted to yieldingly retain the cross-bar in 60 its normal position; and means for guiding and horizontally moving the said cross-head, substantially as described.

Brantford, January 19, 1903.

FREDERICK THOMAS WILKES.
